US00D893016S

(12) **United States Design Patent** (10) **Patent No.:** **US D893,016 S**
(45) **Date of Patent:** **** Aug. 11, 2020**

(54) **NASAL CANNULA ASSEMBLY**

(71) Applicant: **Fisher & Paykel Healthcare Limited**,
Auckland (NZ)

(72) Inventors: **Daniel Charles Wilson**, Auckland
(NZ); **Chelsea Erin Johnson**, Auckland
(NZ); **Leon Tyler Stanley**, Auckland
(NZ); **Michael Paul Ronayne**,
Auckland (NZ); **Anna Rose Northey**,
Auckland (NZ)

(73) Assignee: **Fisher & Paykel Healthcare Limited**,
Auckland (NZ)

(**) Term: **15 Years**

(21) Appl. No.: **29/714,221**

(22) Filed: **Nov. 21, 2019**

Related U.S. Application Data

(60) Continuation of application No. 29/677,003, filed on
Jan. 16, 2019, now Pat. No. Des. 870,878, which is a
division of application No. 29/627,024, filed on Nov.
21, 2017, now Pat. No. Des. 849,242.

CLAIM

The ornamental design for a nasal cannula assembly, as shown and described.

DESCRIPTION

FIG. 1 is a top, front and right side perspective view of a nasal cannula assembly embodying our new design.

FIG. 2 is a top, rear and right side perspective view thereof.

FIG. 3 is a top view thereof.

FIG. 4 is a bottom view thereof.

FIG. 5 is a right side view thereof.

FIG. 6 is a left side view thereof.

FIG. 7 is a front view thereof; and,

FIG. 8 is a rear view thereof.

Broken lines are used to illustrate portions of the nasal cannula assembly which form no part of the claimed design.

1 Claim, 6 Drawing Sheets
